REFRIGERATOR DOOR

Carl Louis Otto, New York, N.Y., and Börje Birger Grönqvist, Viggbyholm, Sweden, assignors to Aktiebolaget Electrolux, Stockholm, Sweden, a corporation of Sweden

Filed Sept. 22, 1958, Ser. No. 762,468

12 Claims. (Cl. 20—35)

This invention relates to refrigerator doors.

An object of the invention is to provide an improved refrigerator door of simplified construction which can be readily assembled.

Another object of the invention is to provide an improved refrigerator door having reinforcing structure at the front face thereof which is effectively concealed from view by a trim strip.

Further objects and advantages of the invention will become apparent as the following description proceeds, and the features of novelty which characterize the invention will be pointed out in the claims annexed to and forming a part of this specification.

For a better understanding of the invention, reference may be had to the following description taken in connection with the accompanying drawings, in which:

Fig. 1 is a front elevation of a refrigerator cabinet provided with a door embodying the invention;

Fig. 2 is a side elevation of the refrigerator cabinet illustrated in Fig. 1;

Figs. 3 and 4 are enlarged horizontal and vertical sectional views, partly broken away, taken at lines 3—3 and 4—4, respectively, of Fig. 1, to illustrate details of the door;

Fig. 5 is an enlarged fragmentary front elevation of the door shown in Figs. 3 and 4, partly broken away and in section, to illustrate corner details of the door;

Fig. 6 is an enlarged fragmentary vertical sectional view taken at line 6—6 of Fig. 1;

Fig. 7 is an enlarged fragmentary front elevation of parts shown in Fig. 5, certain other parts being omitted to illustrate details more clearly;

Fig. 8 is a vertical elevation view taken at line 8—8 of Fig. 7; and

Fig. 9 is a horizontal sectional view taken at line 9—9 of Fig. 8.

In the drawings, a refrigerator cabinet 10 is provided with a door 11 for closing the front access opening of the cabinet interior 12. The cabinet 10 includes an inner shell 14 which forms the cabinet interior 12 adapted to be cooled by suitable refrigeration apparatus. An outer shell 15, which is formed with a flat top 16 and lateral side walls 17 perpendicular thereto, is in spaced relation with the inner shell 14 and the space therebetween is filled with suitable insulation 18. About the front access opening is provided a breaker strip 19 which is formed of suitable insulating material and bridges the gap between the forward edges of the inner and outer shells 14 and 15, respectively.

The multi-sided door 11 comprises inner and outer wall members 20 and 21 having a suitable insulating medium 22 therebetween. As best seen in Figs. 3 and 4, the inner wall member 20, which may be formed of suitable plastic material, is of dish-like form having a rim or ledge 20a about its periphery which is essentially parallel to the outer wall member 21. A gasket 22 is provided at the ledge 20a for effectively sealing the door 11 in its closed position.

The gasket 22 preferably comprises a strip of resilient or elastic material, such as rubber or soft plastic, for example, provided with a flat portion 22a and a hollow striking bead 22b which forms an air-tight seal when it contacts the front marginal portions 23 of the outer shell 15. The hollow bead 22b and flat portion 22a are connected along one edge at 22c and spaced to form a groove 22d which receives the rim or ledge 20a of the inner wall member 20.

10 In accordance with this invention, the outer wall member 21 comprises the main supporting frame of the door 11 and is provided with reinforcing structure at its front face. In the preferred embodiment illustrated, the reinforcing structure comprises flanges 24, 25, 26 and 27 which project forward from the periphery of the front face of the outer wall member 21. As best seen in Fig. 7, the outer wall member 21 is notched at the corners at 28 to provide gaps 29 between the ends of adjacent flanges 24 to 27.

20 As shown in Figs. 3, 4, 8 and 9, the flanges 24 to 27 are substantially perpendicular to the flat outer wall member 21. The outer end portions of the flanges 24 to 27 are bent inwardly from the sides of the outer wall member to form lips or outer flange portions 24a, 25a, 26a and 27a which are essentially parallel to the outer wall member and spaced forwardly therefrom.

As best shown in Fig. 7, the corners of the outer wall member 21 are reinforced by brackets 30 having curved intermediate portions 30a at the gaps 29 and flat arms 30b and 30c which extend into the U-shaped channels formed by the flanges 24 to 27 and lips or outer flange portions 24a to 27a. The flat arms 30b and 30c of the corner brackets 30 bear against the inner surfaces of the flanges 24 to 27 and are fixed thereto at 31, as by spot welding, for example.

30 The door 11 may be hinged to the front of the cabinet 10 in any suitable manner (not shown). If desired, the corner brackets 30 may be employed as regions to which hinge parts may be secured to the door. In such case, the vertically disposed arms 30b of the corner brackets 30 at the hinge side of the door may be provided with threaded openings 32 provided in the flange 27 and at which regions hinge parts may be threadedly secured.

35 A suitable trim strip is provided about the periphery of the outer wall member 21 for the purpose of concealing the reinforcing flanges 24 to 27 from view and providing a door having a neat and decorative appearance. In the preferred embodiment illustrated, the trim strip comprises a plurality of sections 124, 125, 126 and 127 which in cross-section are of trapezoidal form, the longer of the two parallel sides 124a to 127a and 124b to 127b being provided with elongated slots 124c to 127c.

40 In Figs. 3 and 4 it will be seen that the shorter of the two parallel sides of the trim strip sections, viz., sides 124a to 127a, are parallel to and in contact with the lips or outer flange portions 24a to 27a; and the longer of the two parallel sides, viz., sides 124b to 127b are parallel to and bear against the front face of the outer wall member 21. The sides 124d to 127d of the trim strip sections are parallel to the forwardly projecting reinforcing flanges 24 to 27 and in contact therewith.

45 The fourth and last sides 124e to 127e of the trim strip sections are inclined with respect to the sides 124d to 127d and slope inwardly from the sides of the outer wall member 21 in a direction extending from the front to the rear of the trim strip sections 124 to 127.

50 The elongated slots 124c to 127c are sufficiently wide so that the trim strip sections 124 to 127 can be moved over the lips or outer flange portions 24a to 27a of the flanges 24 to 27 to the positions illustrated in Figs. 3 and 4.

55 Essentially, the sides 124b to 127b of the trim strip

sections form the inner bent longitudinal edge portion of the trim strip which is concealed from view and bears against the front face of the outer wall member 21.

The outer longitudinal edge portions of the trim strip sections 124 to 127 are bent back upon themselves to form grooves 124f to 127f which are disposed essentially in planes passing through the forwardly projecting flanges 24 to 27, respectively. The bent outer longitudinal edge portions of the trim strip sections bear against the part 22c of the gasket 22 and also are concealed from view, as seen in Figs. 3, 4 and 6.

The grooves 124f to 127f of the trim strip sections receive the short arms 32a of angle members 32, the longer arms 32b of which bear against the rear face of the outer wall member 21 at regions directly opposite the sides 124b to 127b of the trim strip sections. The ledge 20a of the inner wall member 20, gasket 22, arms 32b of angle members 32, outer wall member 21 and sides 124b to 127b of the trim strip sections 124 to 127 are formed with aligned openings which are distributed about the periphery of the door 11 to receive tightening screws 33 for firmly securing the door parts together, as shown in Fig. 6. It will be evident that the hollow bead 22b must be raised from its normal position when the screws 33 are being inserted in position and tightened to secure the door parts together.

Additional screws 34 are illustrated in Figs. 3 and 4 which are disposed at regions between the regions at which screws 33 are provided for securing the door parts together. The screws 34 pass through aligned openings in the outer wall member 21 and sides 124b to 127b of the trim strip sections to properly position and locate the trim strip sections at the front face of the outer wall member. In this way, the number of door parts that must be handled when the screws 33 are employed in the final assembly of the door 11 is materially reduced.

In Figs. 3 and 4 it will be seen that the heads of the screws 34 are disposed in openings 32c formed in the longer arms 32b of the angle members 32. In this way, the angle members 32 may be placed in position against the rear face of the outer wall member 21 after the trim strip sections 124 to 127 have been secured thereto by the screws 34. It should be evident that the screws 34 need not be employed and all of the door parts may be secured together by the screws 33. However, when this is done, considerably more door parts must be handled at one time in the final assembly of the door 11.

As shown in Fig. 5, the ends of the trim strip sections 124 to 127 are at angles to their longitudinal axes and gaps 35 are formed between the ends of adjacent trim strip sections at the corners of the outer wall member 21. While the trim strip sections 124 to 127 may be of such length that relatively small gaps are formed between the ends of adjacent sections which may be welded to one another, for example, the fabrication of the door 11 is simplified considerably by providing corner members 36 having grooves 36a to receive the end edges of adjacent trim strip sections 124 to 127. The portion of groove 36a receiving the end edge of the side 126d of trim strip section 126 is illustrated in Fig. 5. By providing grooves 36a of ample depth in the corner member 36, any variations in the relative positions of the trim strip sections at the front face of the outer wall member 21 can readily be compensated to facilitate the assembly of door parts in accord with the invention.

With the door 11 in its closed position, the flanges 24 to 27 are perpendicular to the front of the cabinet 10. Also, the flanges 24, 26 and 27, as well as the sides 124d, 126d and 127d of the trim strip sections, are substantially in alignment with the top 16 and lateral side walls 17 of the cabinet to provide a refrigerator which is attractive and neat in appearance.

In the preferred embodiment illustrated and just described, the trim strip sections 124 to 127 are formed

from flat stock and bent into the desired shape in any suitable manner. However, it should be understood that the trim strip sections may be formed in any other suitable way, as by extrusion, for example.

It will now be understood that an improved refrigerator door has been provided in which the flanges extending forward from the front face of the outer wall member are effectively utilized to reinforce the door. This arrangement is especially advantageous when the outer wall member constitutes the main supporting frame of the door. In turn, the trim strip sections, which overlie the reinforcing flanges and conceal the latter from view, are secured in position at the front face of the outer wall member and protected to a great extent by the reinforcing flanges. This produces an inexpensive and easily manufactured construction.

While a single embodiment of the invention has been shown and described, such variations and modifications are contemplated as fall within the true spirit and scope of the invention, as pointed out in the following claims.

What is claimed is:

1. A refrigerator door including inner and outer wall members having an insulating medium therebetween, said outer wall member having a flange at its periphery which projects from the front face thereof, and an elongated trim strip which overlies said flange and conceals the latter from view, the longitudinal edge portions of said trim strip being bent and concealed from view, means for fastening said trim strip to said outer wall member, said fastening means cooperating with at least one of the bent longitudinal edge portions of said trim strip, said one longitudinal edge portion of said trim strip being bent back upon itself to form a groove disposed essentially in a plane passing through said flange, and an angle member having a pair of arms, one of said arms nesting in said groove and the other arm being fixed to the rear side of said outer wall member.

2. A refrigerator door as set forth in claim 1 in which the other arm of said angle member is fixed to the rear side of said outer wall member by said trim strip fastening means.

3. A refrigerator door including inner and outer wall members having an insulating medium therebetween, said outer wall member having a flange at its periphery which projects from the front face thereof, and an elongated trim strip which overlies said flange and conceals the latter from view, the longitudinal edge portions of said trim strip being bent and concealed from view, one longitudinal edge portion of said trim strip being bent back upon itself to form a groove disposed essentially in a plane passing through said flange, an angle member having a pair of arms, one of said arms nesting in said groove and the other bearing against the rear face of said outer wall member, the other longitudinal edge portion of said trim strip being bent to form a trim strip side bearing against the front face of said outer wall member, said outer wall member having openings, and means passing through said openings for fastening the other arm of said angle member and said trim strip side to said outer wall member.

4. A refrigerator door as set forth in claim 3 in which said inner wall member is formed with openings, said fastening means also passing through the openings in said inner wall member.

5. In an insulated refrigerator door, a substantially flat outer wall member having at its periphery an integrally formed flange which includes a first section that projects forward from the front face of the wall member and is substantially perpendicular thereto and a second outer section that projects inwardly from the periphery of the wall member at the forward end of the first section and is substantially parallel to the front face of the wall member and spaced therefrom, an elongated four-sided trim strip, means to fix the trim strip to the outer wall member, the trim strip embracing said flange and having integrally

formed sides including first and second parallel sides which respectively overlie the front face of the outer wall member and the front surface of the second outer flange section, a third side which is perpendicular to the first and second sides and overlies the outer surface of the first flange section, a fourth side which extends alongside the third side and is spaced from the periphery of the outer wall member, the fourth side being united to the first and second sides at regions thereof most remote from the periphery of the outer wall member, and the first side extending from the fourth side toward the periphery of the outer wall member and being concealed from view.

6. An outer wall member for an insulated refrigerator door as set forth in claim 5 in which the first and third sides of the trim strip have a gap therebetween through which the flange projects forward from the front face of outer wall member.

7. An outer wall member for an insulated refrigerator door as set forth in claim 6 in which the means to fix the trim strip to the outer wall member comprises fastening structure cooperating with the first side of the trim strip which is concealed from view.

8. An outer wall member for an insulated refrigerator door as set forth in claim 5 in which the third side of the trim strip extends rearward past the periphery of the outer wall member and the rear free end thereof terminates at a region at the back side of the wall member, the means to fix the trim strip to the outer wall member comprising structure cooperating with the rear free end of the third side of the trim strip.

9. An outer wall member for an insulated refrigerator door as set forth in claim 8 in which the rear free end of

the third side of the trim strip is bent back upon itself to form a groove with the extreme rear edge of the third side concealed from view, the structure forming a part of the trim strip fixing means including a part having one portion disposed in the groove and another portion against the back side of the outer wall member.

10. An outer wall member for an insulated refrigerator door as set forth in claim 5 in which said four-sided trim strip is of trapezoidal form, the fourth side of the trim strip sloping away from the periphery of the outer wall member in a rearward direction from the second to the first sides of the trim strip.

11. An outer wall member for an insulated refrigerator door as set forth in claim 5 in which the wall member is rectangular and the integrally formed flange and elongated trim strip are both formed with gaps at the corners of the outer wall member, and members bridging the gaps of the trim strip at the corners of the outer wall member.

12. An outer wall member for an insulated refrigerator door as set forth in claim 11 which includes angle members which bridge the gaps of the flange at the corners of the outer wall member and are fixed to the flange at both sides of each gap, said angle members being concealed from view by the members bridging the gaps of the trim strip at the corners of the outer wall member.
